UNITED STATES PATENT OFFICE.

AUGUSTE EUGÈNE HENRI GRAVILLON, OF PARIS, FRANCE.

SPEED-REDUCING CONTROL.

Application filed October 23, 1926, Serial No. 143,771, and in France November 4, 1925.

The object of my invention is to provide a single or double speed reducing control more especially suitable for variable air condensers but also usable wherever a movable part or a set of movable parts is desired to be rotated at as slow as possible a speed relative to a fixed part or to a fixed set of parts.

My device consists essentially in the combination with the main control that rotates the movable part of the apparatus or instrument at an unreduced speed (an operating knob in the particular case of variable condensers for radio instruments), of an auxiliary control connected with the said main control through a suitably-guided flexible shaft or such like. This shaft may or may not be provided with an intermediate speed reducing device, and its free end carries a suitable movable friction part which bears on a fixed member that may or may not be part of the instrument, such connection permitting the main operating control and, hence, the movable part of the instrument to be driven at a speed proportional to the diameter of the above mentioned friction part.

Figures 1, 2, and 3 of the accompanying drawing are vertical sectional views of three embodiments of the invention, all three being based upon the same principle.

The control device shown by Figure 1 is especially designed for ready fitting on any type of variable air condenser for radio sets.

A denotes the spindle on which are secured the movable blades B of the condenser, the upper cheek plate of which is designated C. The panel on which the condenser is set in the usual manner is indicated at D.

E is the main operating button knob that is fastened on an inner tube F, by means of which latter it is secured on spindle A, said knob E permitting blades B to be rapidly moved.

According to my invention, the knob E is formed with a passage through which extends a rigid tubular member G, of bent shape, rigidly attached at one end to tube F and terminating at the other end at H beneath the dial portion I of said knob. Within said tubular member G is housed a flexible shaft J, preferably comprising two portions the spirals of which run in opposite directions so as to reduce over-suppleness which might hinder perfect control efficiency. On

the end K of flexible shaft J is secured a small operating button L, while on its other end is secured a roller M bearing with suitable pressure on panel D.

The operation of this device will now be readily understood. When I turn the main knob E, I obtain rapid displacement of blades B. If I wish the blades to be actuated at a reduced speed, I merely have to turn the auxiliary knob or button L, whereby the flexible shaft J is rotated and, in turn, rotates roller M. Since this roller bears on the fixed panel D, there will be produced an extremely slow motion of the main knob E and, hence, of spindle A and blades B connected thereto.

In the example shown by Figure 2, the flexible connection J runs through spindle A, on which are mounted the movable blades B, and the roller M comes to bear on the lower cheek plate C' of the condenser. The operation of this device is analogous to the one of Figure 1.

The embodiment illustrated by Figure 3 offers the peculiarity of comprising a double speed reduction. For this purpose, the auxiliary operating knob or button L has a small bevel pinion N meshing with a larger bevel pinion O secured to the flexible shaft J, which latter, as in the preceding case, has a terminal roller M that bears on the fixed panel D. A spring P, or any other suitable contrivance, keeps parts N and O in mesh for driving the flexible shaft. As will be realized, the speed transmitted to spindle A is, therefore, reduced a first time by parts N and O and a second time by friction roller M.

The speed reducing device N—O can be positioned at any point on the flexible shaft, and in any and all cases the friction part M can be constituted by a toothed wheel meshing with a circular rack provided for the purpose.

I wish it to be clearly understood that I reserve the right to modify or alter the above described speed reducing devices or parts according to the particular uses for which they may be intended without being deemed to depart from the scope of my invention.

I claim as my invention:

1. A speed-reducing control for instruments embodying a movable part and a spindle whereto such part is attached, comprising

ing a main knob fixed to said spindle to rotate the same and the movable part at unreduced speed when directly actuated; an auxiliary knob surmounting the main knob; a flexible element attached at one end to the auxiliary knob to be rotated by the same and connected intermediate its ends with the main knob to transmit such rotation thereto; and a friction member on the other end 10 of the transmission element to engage and move over a stationary part of the instrument and thereby reduce the speed of rotation of the main knob by said transmission element.

15 2. A speed-reducing control for instruments embodying a movable part, comprising a main rotary operating element connected to drive the movable part at unreduced speed when directly actuated, and 20 having a passage formed through it; an auxiliary rotary operating element; a rigid tube mounted in said passage and securely connected at one end with the main operating element; a flexible shaft passing 25 through said tube and projecting beyond the same at opposite ends, one end being attached to the auxiliary operating element to be rotated by the same and to transmit such rotation to the main operating element; and 30 a friction member on the other end of said shaft to engage and move over a stationary part of the instrument and thereby reduce the speed of rotation of the main knob by the shaft.

35 3. A speed-reducing control, according to claim 2, in which a rigid tube is mounted in a passage formed through the main knob, through and beyond which tube the flexible

transmission element extends, said tube being fastened at one end to said main knob. 40

4. A speed-reducing control for instruments embodying a movable part, comprising a main rotary operating element connected to drive the movable part at unreduced speed when directly actuated; an auxiliary operating element for said movable part; a flexible shaft connection between the auxiliary and main operating elements for transmitting the rotary movement of the former to the latter at a reduced 45 speed; and means associated with said shaft for reducing the speed of rotation of the main operating element by the shaft.

5. A speed-reducing control for instruments embodying a movable part, comprising a main rotary operating element connected to drive the movable part at unreduced speed when directly actuated; an auxiliary operating element for said movable part; a flexible shaft connection between the auxiliary and main operating elements for transmitting the rotary movement of the former to the latter; and a friction element associated with said shaft to engage 50 and move over a stationary part of the instrument and thereby reduce the speed of rotation of the main operating element by the shaft. 55

6. A speed-reducing control, according to claim 5, in which the friction element comprises a roller attached to the flexible shaft and engaging a stationary part of the instrument. 70

In testimony whereof I affix my signature.

AUGUSTE EUGÈNE HENRI GRAVILLON.
